[57] **CLAIM**

The ornamental design for a vertically extending divider for use in a filing system, substantially as shown and described.

DESCRIPTION

FIG. 1 is a front elevational view of a vertically extending divider for use in a filing system showing my new design;

FIG. 2 is an elevational view of the right edge thereof;

FIG. 3 is a top plan view thereof;

FIG. 4 is an elevational view of the left edge thereof;

FIG. 5 is a rear elevational view thereof; and

FIG. 6 is a bottom plan view thereof.
